(57) **CLAIM**

An ornamental design for a tool-free hanger.

DESCRIPTION

FIG. 1 is a perspective view of my new design for a tool-free hanger;

FIG. 2 is a rear view thereof;

FIG. 3 is a right side view thereof; and,

FIG. 4 is a top view thereof.

The broken lines immediately adjacent the shaded areas represent the bounds of the claim and all other broken lines are for illustrative purposes only. None of the broken lines form part of the claimed design.
